After long experience with various methods of cleaning the folding blades of a folding machine, I have found that the best method is to provide a pair of stationary wiping cylinders which are provided with a series of folding blades which are mounted on a shaft which is rotated by a motor. The folding blades are arranged so that they will be in contact with the wiping cylinders at different points during each revolution of the cylinder, and the wiping cylinders are arranged so that they will be in contact with the folding blades at different points during each revolution of the cylinder.

UNITED STATES PATENT OFFICE

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA

FOLDING BLADE CLEANING DEVICE

Application filed June 14, 1928, Serial No. 285,305. Renewed March 9, 1931.

This invention relates to a device for cleaning the folding blades of a folding machine while the machine is in operation.

The principal objects of the invention are to provide means connected with the folder for cleaning both sides of the folding blades during each operation of the machine, and thus keeping the blades free from ink and preventing the smutting of the papers by the accumulation of ink on these blades; and (in the preferred form) to provide such device in an automatic form operated by the folder.

Other objects and advantages of the invention will appear hereinafter.

Reference is to be had to the accompanying drawings in which

Fig. 1 is an end view of a folding machine, partially diagrammatic in form, showing a preferred form of this invention;

Fig. 2 is a sectional view of the cleaning means and folding blade;

Fig. 3 is a side view of the folding cylinder and cleaning means, and

Figs. 4 and 5 are views similar to Fig. 2, showing modified forms.

Folding cylinders on newspaper printing presses are equipped with two folding blades which fold the paper into a half page fold and tuck it into the folding rolls. As the papers carry freshly printed matter and this printed surface comes into contact with both sides of each folding blade, it is found that an accumulation of ink appears on the blades after a short time. This has a tendency to smut subsequent papers. This invention is designed to remove this ink from the folding blades so as to avoid this difficulty.

Referring to Figs. 1, 2 and 3, I have shown the invention as applied to a folding couple comprising a folding cylinder 10 and a cutting cylinder 11. The folding cylinder is provided with folding blades 12 as usual, which deliver the folded product into contact between the folding rolls 13. Each folding blade is mounted on a shaft 14 which ex-

tends across the machine, and is operated through a stationary gear 15 and a set of gears 16. Thus the folding blades rotate on their own axes while the folding cylinder is in operation, and in the design shown each folding blade is projected outwardly in a radial direction three times during each rotation of the folding cylinder. At one of these points it tucks the folded product into the bite of the folding rolls.

In accordance with the present invention, I make use of the fact that each blade 12 moves out radially at other points and clears the blades when they so project, preferably at one of the other points in the circumference of the folding cylinder. For this purpose, I provide a pair of rolls 17 covered with a layer of felt or rubber 18 for rubbing the ink off the opposite surfaces of each blade when it comes into radial position.

The rolls 17 extend throughout the length of the cylinder 10 and are provided with gears 19 by which they are geared together to rotate. On the same shaft with the lower gear 19 is a gear 20 which meshes with a gear 21 on the folding cylinder, thus keeping these rolls in constant rotation throughout the operation of the folding cylinder. It will be seen therefore that as the blade comes to a point between these rolls, its opposite sides will be wiped free of ink and then the blade will pass out of contact with them as indicated in dotted lines in Fig. 2. The blades do not always come into contact with the same spots on the wiping rolls, so these surfaces last a long time without becoming saturated with ink.

It is not necessary that the cleaning device be movable or rotary, and in Fig. 4, I have shown a pair of stationary blocks 23 each covered with a layer of rubber or felt 24. The surfaces between which the blade 12 engages are convex as in the case of the rollers previously described, but a cleaning action is secured which is sufficient for the purpose,

except that the pieces of felt or rubber 24 will not last as long as in the case of a movable surface like the rotary rolls 17 because the blades always engage these surfaces in the same place. In Fig. 5, I have shown a pair of brushes 25 for the same purpose, the operation of which will be obvious.

It will be seen, therefore, that the folding blades are cleaned continually while the folding cylinder is running, thereby obviating all the necessity of stopping the press for cleaning these blades and saving considerable time and also assuring the production of clean products or at least preventing the smutting of the products at this particular point.

Although I have illustrated and described only three forms of the invention, I am aware of the fact that other modifications can be made therein by any person skilled in the art without departing from the scope of the invention as expressed in the claims. Therefore, I do not wish to be limited to the exact form shown, but

What I do claim is:

25. 1. The combination with a folding cylinder having a folding blade, of means located adjacent to the cylinder for engaging the side of the blade and wiping the ink therefrom.
30. 2. The combination with a folding cylinder having a folding blade arranged to be projected radially from the cylinder a plurality of times during each revolution, of means located adjacent the cylinder for wiping the surface of the blade as it projects therefrom.
35. 3. The combination with a folding cylinder and a folding blade arranged to be projected radially from the surface of the cylinder a plurality of times during each revolution, and folding rolls through which the blade is projected at one point, of a pair of wiping devices located at another point at which the blade is projected for receiving the blade between them and wiping the ink from both sides thereof.
40. 4. The combination with a folding cylinder and a folding blade arranged to be projected radially from the surface of the cylinder a plurality of times during each revolution, and folding rolls through which the blade is projected at one point, of a pair of wiping rolls located at another point at which the blade is projected for receiving the blade between them and wiping the ink from both sides thereof, said wiping rolls being covered with a soft material, and means for rotating said rolls while the blade is between them.
45. 5. The combination with a folding cylinder having folding blades arranged to be projected radially from the cylinder a plurality of times during each revolution, of a pair of rolls located adjacent the cylinder for wiping the surface of each blade when it projects therefrom, and gearing connected with the

folder for constantly rotating said rolls while the folder is running.

6. The combination with a folding cylinder having folding blades, of a pair of stationary brushes located adjacent to the cylinder for engaging the opposite sides of each blade and wiping the ink therefrom, said brushes having convex surfaces adjacent each other.

7. The combination, in a folding machine adapted to fold printed sheets, of a folding blade for folding the said sheets, and means for wiping the ink from the said folding blade.

In testimony whereof I have hereunto affixed my signature.

HENRY A. WISE WOOD.
